UNITED STATES PATENT OFFICE.

GLENN BERTELSMANN, OF INDIANAPOLIS, INDIANA, ASSIGNOR TO ELLEN A. BERTELSMANN, OF INDIANAPOLIS, INDIANA.

HAND PUMP.

Application filed August 6, 1923. Serial No. 655,987.

To all whom it may concern:

Be it known that I, GLENN BERTELSMANN, a citizen of the United States, and a resident of Indianapolis, county of Marion, and State of Indiana, have invented a certain new and useful Hand Pump; and I do hereby declare that the following is a full, clear, and exact description thereof, reference being had to the accompanying drawings, in which like 10 numerals refer to like parts.

This invention relates to a manually operative air pump construction, although certain features thereof may be incorporated in other types of air pumps.

15 The chief object of the invention is to construct an air pump in such a manner that the pump will operate with increased efficiency for the same effort than has heretofore been possible in pump constructions 20 of a similar kind.

Another object of the invention is to construct the pump in such a manner that the machine work upon the parts will be reduced to a minimum, thereby reducing the cost of 25 producing such an efficient pump.

The chief feature of the invention consists in the novel base of the pump construction which is adapted to support the pump, to provide intake means for said pump, to provide 30 discharge means for said pump, and to provide an outlet which is adapted to receive suitable pressure indicating means.

Another feature of the invention consists in the particular construction of the attaching 35 nozzle, whereby the pump is operatively connected to the usual valve stem of the article to be inflated in an improved manner.

The full nature of the invention will be understood from the accompanying drawings and the following description and 40 claim.

In the drawings, Fig. 1 is a side elevational view of a unitary pump construction showing all the parts thereof. Fig. 2 is a 45 plan view of the pump, and particularly the base thereof, and is taken on line 2-2 of Fig. 1 and in the direction of the arrows. Fig. 3 is an end elevational view of the base and a part of the pump and is taken 50 at right angles to Fig. 1. Fig. 4 is a central sectional view of the pump base, cylinder and piston. Fig. 5 is a central view taken on line 5-5 of Fig. 4. Fig. 6 is a central sectional view of the attaching nozzle showing the same in attached relation to and

upon the valve. Fig. 7 is a sectional view of the base of the invention showing a modification thereof. Fig. 8 is a sectional view of the invention taken on the line 8-8 of Fig. 7 and shows the pressure indicating means in the pressure indicating position. Fig. 9 is a central sectional view of a valve connection provided in the hose connection of the pump and is adapted to receive pressure indicating means shown positioned adjacent thereto.

In the drawings 10 indicates a pump cylinder having threaded ends. In said pump cylinder is a piston rod 11 slidably supported by a closure cap 12 having an air port 13 therein for relieving back pressure on the piston. Within the cylinder and having a threaded connection with the free end of said piston rod 11 therein, is a piston, including a base or body portion 14 and a packing member 15, as well as two securing members 16 and 116, the former being of fibre and the latter flattened to form a nut with cylindrical cup, for maintaining the packing member in association with the body portion 14 to maintain said packing member in complete circumferential engagement with the inner wall of the cylinder. A suitable handle 17 positioned upon the outer free end of the piston rod 11 is adapted to reciprocate said piston means in said cylinder. The other threaded end of the cylinder 10 is secured to a foot base herein designated generally by the numeral 18. The foot base 18 is provided with two apertures 19 upon opposite sides of the cylinder securing portion thereof, and engageable in said recesses 19 are the free ends of a U-shaped foot rest 20, the free ends of which extend angularly of the rest body portion and are seatable in said recesses. The foot rest 20, therefore, is horizontally supported upon the foot base 18 and is adapted to be positioned as shown in Fig. 1, or is adapted to be moved into collapsed relation with said cylinder in the well known manner. Also associated with the base 18 is a suitable hose 21 which is provided upon its free end with a valve connection or nozzle 22, the details of which are illustrated in Fig. 6, and which will be described later more specifically.

Reference will now be had to Figs. 2, 3, 4 and 5, wherein the detailed construction of the valve mechanism associated with the pump is illustrated. As shown clearly in 110

Fig. 2, the base 18 comprises a central body portion with two opposite extensions, one of which is elongated. Extending through said base from one extension to the other is a channel 25 having a communicating outlet 26 connecting said channel with the interior of the cylinder 10. Also communicating with said channel 25 is a chamber 27 formed in the single projection of said base 18, and said chamber serves as an intake chamber and a spring chamber. The chamber is provided with a threaded opening 28. A closure member 29 has a threaded engagement with said threaded end 28 and is also centrally apertured at 30. Communicating with said central aperture 30 is a plurality of transverse ports or channels 31 communicating with the atmosphere. In axial alignment with the channel 30 is a recess 32, and in said recess is slidably supported a hollow valve stem 33 carrying upon its lower free end a valve 34 which is positioned in the chamber 27. Concentric with said valve is a coiled spring 35 for normally maintaining said valve in closed position. Upon the upward or suction stroke of the piston in the cylinder 10, the atmospheric pressure engages upon the valve 34 and unseats the same, simultaneously compressing the spring 35; since upon said upward stroke of the piston there is created a vacuum in the cylinder 10. As shown in Fig. 4, the valve stem extends loosely through the channel 30. Upon the return or compression stroke of the piston, the spring 35 seats the valve 34, and subsequent pressure through the compression in the cylinder seals said valve on its seat.

Figs. 3, 4 and 5 illustrate in detail the discharge mechanism of the pump. That portion of the channel 25 which extends into the elongated projection hereinbefore mentioned communicates with a channel 36 which is extended at 37. Said extended channel 37 is again extended at 38, and branching from said extension and communicating therewith is a pair of oppositely extending channels 39 and 40. The channel 38 adjacent its outer end is provided with a threaded surface, and positioned within said channel 38 and having a driven fit in the channel portion 37 is a tubular member 41 which extends through said channel 38 and provides an inner passage and a concentric outer passage. Secured in the threaded portion of the channel 38 is a cap or closure member 42 suitably recessed at 43 and having a chamber 44 communicating therewith. Slidably supported in said recess is a valve stem 45 carrying on its free end in the chamber 44 a valve 46, which valve by the tire pressure or vacuum in channel 25 is normally seated upon the end of the tube 41 to seal the same until such time as pressure within the tube 41 unseats said valve and permits the com-

pressed air to escape from the channel 36 to the concentric channel in the chamber 38, and thence to either or both of the branching channels 39. Thus, upon the intake stroke of the piston, the suction seats the valve 46 and unseats the valve 34; while upon the compression stroke of the piston, the valve 46 is unseated and the valve 34 is seated.

The branched channel 38, see Fig. 5, is enlarged at 48 and is threaded at its outer end. A hose attaching stem 49 having the usual channel 50 therethrough has a threaded connection with said base 18, and said channel 50 communicates with the chamber 48, and, therefore, the branching channel 39 also communicates with the hose 21 which is secured to the foot base 18 by means of the barbed attachment 49. The other end of the hose 21 is similarly secured to a barbed supporting portion 51 of the body portion 22 of said discharging nozzle. The discharging nozzle body portion 22 is apertured at 52, and positioned in said aperture is a stem 53 concentric therewith and providing an annular discharge passage therebetween. The body portion 22 is enlarged at 54 and is provided with a spherical surface. The connecting means includes a knurled portion 55 and a spherical engaging portion 56 for engaging the flange portion or enlarged portion 54 thereby forming a ball joint. The knurled finger portion 55 is provided with a threaded interior which is adapted to engage the threaded exterior 57 of a tire valve 58, said valve including the usual valve portion 59 and stem 60, said valve being normally seated by means of the spring 61. Included between the finger piece 55 and the flange 54 is a washer 62 which bears against the projecting portion of the valve stem 57 and maintains a seal between said flange 54 and said valve stem 57 when the discharge nozzle is in seated or closed position. The projecting stem 53 hereinbefore described includes a threaded connection 63, and positioned upon said stem and without said nozzle is a finger piece 64 for threading said stem into and out of said nozzle. Thus, when the stem is normally in lowered position and the finger piece 55 is threaded down upon the valve stem, said stem 53 engages the stem 60 of the valve mechanism in the valve of the article to be inflated and unseats the same. An enlarged portion 65 prevents the escapement of stem 53. Air pressure thereupon is communicated through the hose 21 and branch channel 39 to the chamber 38, which seats the valve 46 until such time as said valve is unseated by the compressed air discharged by said pump. Thus, the air discharged by the pump merely has to lift the valve 46 after its pressure is equal to the pressure in the article to be inflated, and, therefore, does not have to unseat the valve 59 by depressing the same,

and, therefore, compressing the spring 61 at each stroke of the piston. The above, therefore, secures more efficient operation of the pump.

- 5 After the article has been inflated to the desired pressure in order to maintain said pressure, the finger piece 64 is turned outwardly, thereby moving the stem 53 out of engagement from the stem 60, and thereby 10 permitting the valve 59 to be seated through the spring 61 and also the air pressure therein. Thus, there is no loss of pressure from the inflated article when the finger piece 55 is removed from the valve stem. 15 The branch channel 40 is enlarged at 70, and said chamber is threaded at its outer end and is closed by a plug 72, which plug 72 slidably supports the stem 73 of a valve 74, which is seated by air pressure upon the 20 compression stroke of the piston or by the pressure of the air in the article to be inflated when said pressure exceeds atmospheric pressure and the weight of said valve. The valve stem is cut away at 75 to provide a passage therethrough when the valve is unseated. Therefore, until such time as the pressure in the article to be inflated exceeds that of the atmosphere, plus the 25 weight of the valve 74, said valve will open upon the suction stroke. This branch channel 40 is also provided as a bleeder when it is desired to reduce the pressure of the article to be inflated to a desired pressure.

This branch channel also is adapted to 30 receive suitable pressure indicating means, reference now being had to Figs. 7 and 8. When the same is used as an integral part 35 of the pump, the beforementioned closure member and the valve 74 is removed from the chamber 70 and the base 80 of a pressure 40 indicating device 81, including the communicating piston portion 82. Thus, the pressure indicating means will positively register at all times the pressure of the article 45 to be inflated.

Figs. 7 and 8 also illustrate a modified form of the invention, wherein the intake valve mechanism hereinbefore described and clearly illustrated in Fig. 4 is replaced by 50 a substantially similar mechanism, wherein a closure member 129 is substantially similar to the closure member 29 and the transverse or intake ports 131 are substantially

similar to the ports 31, with this exception, however, that the exterior of said closure member 129 is suitably threaded to receive a cylinder or tube 130 having its open end closed by means of a protecting screen 132. The ports 131, therefore, communicate with the tube and with the atmosphere through 60 said screen and tube. Thus, all the air which enters the pump, and the article to be inflated through the tube is screened. This not only prolongs the life of the pump and insures more efficient operation thereof, 65 but also prevents foreign particles from entering the article to be inflated.

In Fig. 9 is illustrated a modified form of the invention, wherein the hose 21 is suitably separated at any desired point and a T connection 140 inserted therein, which T connection is provided with a chamber 141 adapted to receive a valve 142 having the stem 143 slidably supported in a closure member 144 for closing said chamber 141. 70 The pressure indicating means 81 is adapted to be inserted at this point in substantially the same manner as hereinbefore described with the replacement of the valve 74 and closure member 72 as illustrated in Figs. 5 75 and 8.

While the invention has been described in great detail in the beforementioned specifications, it is to be understood that the same is illustrative and not restrictive in character, and that the invention is susceptible of many modifications thereof without departing from the broader features of the invention. 85

The invention claimed is:

A pump construction including a cylinder, a piston therein, a base connected to said cylinder at one end thereof and having enlargements extending oppositely from the cylinder, a check valve controlled intake in 95 one of said enlargements, and a check valve controlled outlet in the other enlargement, a T-shaped channel in the last-mentioned enlargement having its main branch communicating with the outlet, a hose connection 100 in one lateral branch of said T-shaped channel, and a valved outlet for the other lateral branch.

In witness whereof, I have hereunto affixed my signature.

GLENN BERTELSMANN.
